UNITED STATES PATENT OFFICE.

IRA V. SCHOLFIELD, JR., OF SAN FRANCISCO, CALIFORNIA.

AIR-SUPPLY FOR BOILER-FURNACES.

SPECIFICATION forming part of Letters Patent No. 481,831, dated August 30, 1892.

Application filed July 28, 1891. Serial No. 400,991. (No model.)

To all whom it may concern:

Be it known that I, IRA V. SCHOLFIELD, Jr., a citizen of the United States, residing in the city and county of San Francisco, State of California, have invented an Improvement in Air-Supplies for Boiler-Furnaces; and I hereby declare the following to be a full, clear, and exact description of the same.

My invention relates to an improved device and means for supplying air to boiler-furnaces.

It consists of a chamber surrounding the upper part of the furnace, with doors or openings through which air is admitted into the chamber, where it is heated from the furnace and is directed around the sides of the fire-door into the ash-pit below the grate-bars, from which it passes into the fuel-space.

It also consists in certain details of construction, which will be more fully explained by reference to the accompanying drawings, in which—

Figure 1 is a vertical transverse section on the line xx of Fig. 2, looking to the front. Fig. 2 is a vertical longitudinal section through the center of the boiler. Fig. 3 is a longitudinal horizontal section on the line yy of Fig. 1. Fig. 4 is a vertical transverse section on the line zz of Fig. 3, looking toward the rear.

In the present case I have shown my invention as applied to a boiler of that class in which the grate and fire-box are situated in a large flue, which extends through the lower part of the boiler to a combustion-chamber in the rear, from which the products of combustion are returned to the front through small tubes above and around the large flue, these tubes connecting with the uptake and smoke-stack at the front of the boiler.

A is the boiler, and B is a large flue extending through the lower part.

C are the return-tubes, through which the products of combustion reach the smoke-stack.

Within the large tube and near the front is formed a casing D, having a vertical plate or diaphragm a surrounding the upper portion and sides of the front portion of the flue, and having, also, the vertical side plates or diaphragms b and upper and lower horizontal plates c and c' , which form the walls of the opening through which the fuel is introduced to the grate-bars, said plate c' being extended

to the sides of the flue B and provided with openings J, while the plates b and lower side portions of the plate or diaphragm a are provided with openings L for supplying heated air to the furnace above the grate-bars.

F are doors or gates opening through the front of the boiler above the fire-door G, so that air may enter into this casing or chamber through these doors. The doors are made adjustable in any suitable or desired manner to control the admission of air into the casing.

H are the grate-bars within the fire-box, upon which the fuel is burned, and I is the ash-pit beneath these grate-bars. The front of this ash-pit remains closed, and air being admitted through the doors F into the upper part of the casing passes down around each side of the front portion of the fire-box and is delivered through openings J into the ash-pit beneath the grate. The heat radiating from the fire into the casing raises the temperature of this air to a high degree, so that when it is delivered to the fuel it does not reduce the temperature of the latter, and the improvement in the combustion thus caused is very great.

M is the bridge-wall at the rear of the furnace, over which the products of combustion pass to the rear of the boiler.

K K are pipes extending through the front of the boiler beneath the grate and opening through the bridge-wall into the space behind. These pipes are of any suitable or desired size and have controlling valves or gates K', through which a supply of air passes. The air passing through these pipes is also heated from the fire on the grate and is delivered to the space behind the bridge-wall, where it meets the unconsumed products of combustion and supplies a further quantity of air for a more complete combustion of these products.

L L are small holes opening from the chamber or casing D into the furnace above the grate-bars, and these holes supply heated air for more perfect combustion at this point.

The whole device is simple and easily applied to any boiler and is extremely efficient.

Having thus described my invention, what I claim as new, and desire to secure by Letters Patent, is—

An improved return tubular boiler consist-

ing of the combination of a main circular flue B, a casing D, consisting of a vertical plate or diaphragm *a*, surrounding the upper portion and sides of the front portion of the flue, and 5 the plates or diaphragms *b*, *c*, and *c'*, forming the walls of the opening through which the fuel is introduced, said plate *c'* having openings *J*, and the plates or diaphragms *b* and lower side portion of the plate or dia-

phragm *a*, having opening *L* for delivering heated air to the furnace, and the doors *F* and *G*, substantially as herein described.

In witness whereof I have hereunto set my hand.

IRA V. SCHOLFIELD, JR.
